CLAIM

The ornamental design for a dining table, as shown and described.

DESCRIPTION

FIG. 1 is a perspective view of a dining table showing the claimed design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is an enlarged view of the selected portion 8 in FIG.

2.

The broken lines depict portions of the dining table that form no part of the claimed design. The dash dot dash lines in FIGS. 2 and 8 depict the boundary lines of the enlarged view and form no part of the claimed design.

1 Claim, 8 Drawing Sheets
